INVENTOR
Joseph Hirshstein
BY E. E. Huffman
ATTORNEY

UNITED STATES PATENT OFFICE.

JOSEPH HIRSHSTEIN, OF CLEVELAND, OHIO.

DRAIN.

Application filed July 10, 1922. Serial No. 574,005.

To all whom it may concern:

Be it known that I, JOSEPH HIRSHSTEIN, a citizen of the United States of America, residing at the city of Cleveland, county of Cuyahoga, State of Ohio, United States of America, have invented a certain new and useful Drain, of which the following is such a full, clear, and exact description as will enable anyone skilled in the art to which it appertains to make and use the same, reference being had to the accompanying drawings, forming part of this specification.

My invention relates to drains for roofs or floors and particularly to means for forming water tight connection between the drain body and a sheet of water proofing material connected therewith which material is usually referred to in the art as a "flashing".

The object of the invention is to provide clamping means for connecting the flashing to the drain which will be simple and effective and will avoid the use of fasteners, solder or cementing compounds and the necessity of making any holes through the "flashing."

In the accompanying drawings, Figure 1 is a vertical cross section of one type of a drain apparatus embodying my invention; Figure 2 is a side elevation; and Figure 3 an enlarged detail view of the clamping members and associated parts. The drain illustrated is of what is known as the drain double drainage type in which the drain body 1 is provided with an adjustable head 2 adapted to be positioned flush with the floor or roof level (indicated by dotted lines 8) and with a seepage collecting pan or receptacle 3 surrounding the drain body and adapted to discharge into the drain through the openings 9 any liquid which may be collected by the pan. This pan collects liquid which may leak around the outside of the drain and between it and the floor material and in order to protect against cracks or leakage through the floor in any portion of the surface in which the drain is situated it is a common practice in various locations, such as shower bath rooms to extend a sheet of water proofing material 4 over the entire area of the floor and beneath the upper surface thereof. These sheets of water proofing material or "flashing" are commonly of lead. In cement floor constructions they are usually laid on top of the main body of the floor and the finish surface applied on top of the flashing.

As applied to the particular type of drain shown, my invention is directed to means for conveniently and effectively forming a water tight joint between the flashing and the drainage pan or flange 3 and without the use of a plurality of bolts or screws and without the necessity of making holes through this flashing or making soldered or cement connection between the flashing and the drain. As shown in the drawing, the upper surface of the pan or flange 3 is provided with a horizontal seat for the edge of the flashing and above this seat is a clamping ring 5 for holding the flashing firmly in engagement therewith. This clamping ring is forced into clamping position and held in such position by means of pivoted wedge members 6 which are supported on bolts or pivots 7 threaded into the drain body, this body being preferably thickened or reinforced, as shown, at the point where the bolt enters. The pivoted wedging and locking members 6, of which two are shown but of which there may be any desired number, have a portion of their surfaces curved and the relation of this curve to the pivot is such that the turning of the members on their pivots in one direction brings a portion of their surfaces into clamping relation with the clamping ring 5 and by a toggle wedging action apply substantial pressure to the clamping ring. These wedging and locking members 6 are preferably formed with a flat surface whereby they can be driven into firm wedging position by means of a hammer. The frictional engagement between their surfaces and clamping ring 5 and between the clamping ring, flashing, and drain prevents unintentional release of the wedge members. Of course, when these drains are installed in cement this material would also prevent any turning of the members 6 on their pivots and consequent reduction of the wedging pressure. As indicated in Figure 3 which show the wedges in unlocked position, the wedging surfaces of the members 6 are symmetrically positioned so that if the clamping ring 5 should slip circumferentially while one wedging member is being driven to wedging position such slipping would tend to increase the pressure of other wedging members upon the ring. The

clamping ring 5 is preferably in one piece and by using a suitable number of wedge members 6 depending upon the diameter of the ring, it will be apparent that a firm 5 waterproof joint may be readily formed between the flashing and the drain.

Having fully described my invention what I claim as new and desire to secure by Letters Patent of the United States is:

- 10 1. In a device of the class described, the combination of a drain, a sheet of water proof material, a clamping member for holding said material in engagement with the drain, and a pivoted member carried by the drain and bearing on the clamping member to hold it in clamping position.
- 15 2. In a device of the class described, the combination of a drain, a sheet of water proof material, a clamping member for holding said material in engagement with the drain, and a wedging member carried by the drain and adapted to force the clamping member into clamping position.
- 20 3. In a device of the class described, the combination with a drain, a sheet of water proof material, a clamping member for forming a water tight connection between said material and the drain by pressure, a wedging member carried by the drain and 25 adapted to exert a wedging action on the

clamping member to force it into clamping relation and hold it in said relation.

4. In a device of the class described, the combination with a sheet of water proofing material, of a drain provided with a circumferential seat for said material, a clamping ring bearing on said material to hold it in engagement with the seat, a plurality of spaced pivoted wedging members carried by the drain and having surfaces adapted to exert wedging pressure on the clamping ring and to lock it in clamping position as the result of frictional engagement between the connecting parts. 35

5. In a device of the class described, the combination of a drain, a sheet of water proofing material, a clamping ring for holding said material in engagement with the drain, pivotally supported wedging members for exerting pressure on said clamping ring, said wedging members having bearing surfaces whose relation to the pivots and ring is such that slipping of the ring in bringing one member into wedging position will increase the wedging effect of the other 40 50 members. 55

In testimony whereof, I have hereunto set my hand and affixed my seal.

JOSEPH HIRSHSTEIN. [L. 6.]
